UNITED STATES PATENT OFFICE.

LUCIUS T. STANLEY, OF BROOKLYN, NEW YORK, ASSIGNOR TO AUGUSTUS N. LINDSLEY, OF ORANGE, NEW JERSEY.

POCKET-BATTERY.

SPECIFICATION forming part of Letters Patent No. 363,304, dated May 17, 1887.

Application filed March 23, 1886. Serial No. 196,050. (No model.)

To all whom it may concern:

Be it known that I, LUCIUS T. STANLEY, a citizen of the United States, residing at Brooklyn, in the county of Kings and State of New York, have invented certain new and useful Improvements in Pocket-Batteries, of which the following is a specification, reference being had to the drawings accompanying and forming a part of the same.

10 My invention involves certain improvements in the construction of what are commonly known as "pocket-batteries" for physicians' and surgeons' use. Generally these devices consist of a portable case containing a 15 galvanic battery and an induction-coil adapted for use with various kinds of electrode for applying the induced currents to different parts of the human body.

20 My invention relates to this kind of apparatus and is directed to the improvement of the battery, the electrodes, and the general construction of the apparatus, whereby the same is rendered more convenient, simple, and capable of a more general use and application.

25 I shall describe in detail the construction of the apparatus, and then point out the distinguishing features of novelty which constitute my present invention.

30 Referring to the drawings, Figure 1 is a central longitudinal section of the main portion of the apparatus with the electrode-handles in elevation. Fig. 2 is a side view of the upper portion of the case shown in Fig. 1. Fig. 3 is a top view of the electrode constructed for attachment to the battery-case. Fig. 4 is a central longitudinal section of a modification of the battery-case. Fig. 5 is a partly-sectional view of an insulating-handle for an electrode. Fig. 6 is a section of the same on line *x x* in 40 Fig. 5.

45 The apparatus, as a whole, consists of two parts—the case, in which are contained the battery and induction-coil, and the electrode, which may be attached to the case or to a separate handle. There are other accessories, such as a resistance, handle-electrodes, and the like, which will be hereinafter described.

The case A is preferably made in cylindrical form of hard rubber or like material. B

is the cup, also of hard rubber, that contains 50 the battery. It is adapted for attachment to the case A, by a screw-thread or other form of connection. To the top of the case is fitted and secured a spherical cap, C.

I may use any convenient form of battery. 55 In the present case the cup B is partially filled with the exciting solution, and a cylindrical carbon, b, is secured in the cup, being attached to the sides or top of the cup and electrically connected by a wire, a, with a metal band, c, 60 around the orifice in the cup. The zinc element D is inserted in a plug or stopper, E, of any kind. This plug may be of hard or soft rubber or other insulating material, and is fitted to the mouth of the cell B, being adapted 65 to close the same, so as to prevent the escape of the battery-fluid. I also use a drip-cup, F, which is a cylinder of insulating material closed at one end. When the zinc is placed 70 in the battery-cell this drip-cup is placed over the plug or stopper E. On the other hand, when the battery is not in use, the zinc is placed in the drip-cup, and the stopper inverted and forced into the mouth of the battery-cell.

The central portion of the stopper E is of 75 somewhat greater diameter than the ends, and around it is a ring or band, e, of metal in electrical connection with the zinc. On the sides of the drip-cup are two metal strips, d, f, forming spring-contacts that bear, respectively, on the bands e and c when the drip-cup is placed 80 upon the stopper E. The strip d is in electrical connection with a metal pin, g, in the center of the bottom of the drip-cup, and the strip f is in contact with a band, h, of metal 85 around the edge of the drip-cup.

Above the space occupied by the drip-cup is the induction-coil. This consists of the ordinary primary and secondary coils F' G on a core, H. The coil is supported by an insulating-head, b', that is secured rigidly in the case. The head b' carries the vibrating spring-armature c' and the back contact, d'. The opposite or lower end of the coil is protected by an insulating-head, e', to which are secured two 90 contact-springs, one, the spring i, being in position to encounter the pin g, and the other, or spring j, being in position to bear upon the 95

band *h* when the battery-cup is attached to the case and the drip-cup placed over the stopper *E*. The spring *i* is one of the terminals of the primary of the induction-coil. The spring *j* is connected with a metal strip, *k*, laid alongside the coil and ending in a contact-plate or block, *k'*, in the head *b'*.

K is a metal cylinder surrounding the induction-coil and forming a damper for modifying the intensity of the induced currents. The damper is moved by a pin, *l*, extending through a slot in the side of the case *A*.

The cap *C* has two insulated metal strips, *m n*, secured to its inner surface. The strip *m* extends down into the case *A* in front of the contact-piece *k'*, and a slide, *m'*, is used as a circuit-closer to force it into contact with said piece. When this is done the circuit through the primary coil is completed and the vibrator set in operation. One end of the secondary coil is connected to strip *n*, which is connected with a metal ferrule, *N*, on the cap *C*. The other end of the secondary coil is connected to the primary circuit, and the circuit extended thereby to the strip *m*, which connects with an insulated metal socket, *M*. Small perforated metal pins *o o* are set in the cap *C* in electrical contact with the strips *m n*. The terminals of the induction-coil are therefore either the pins *o o* or the socket *M* and ferrule *N*.

The handle-electrodes *O*, with conducting cords and plugs, may be used in the ordinary way with this apparatus by inserting the plugs in the holes in pins *o o*.

I have devised a novel form of electrode for local applications of the current, which is used in connection with the terminals *M N*. This electrode consists of a metal cup, *p*, containing a screw-threaded pin, *p'*, set in an insulating-block, *q*. The electrode is connected to the terminals by inserting the pin *p'* in the screw-threaded socket *M*, which brings the ferrule *N* in contact with the cup *p*. I place over the top of the cup *p* a circular piece of felt or soft material, *t*, having a hole in its center. I then place an insulating-washer, *r*, over the felt and fasten it down securely by a rounded screw-nut, *s*. The edges of the piece of felt are secured by a metal ring, *t'*, forced down around the sides of the cup *p*. This felt is to be dampered and the currents pass between it and the nut *s* through whatever portion of the body the electrode may be applied to.

When the current is to be applied to very sensitive parts of the body, as to the temples and eye, it is not possible often to weaken the current sufficiently by the damper. I therefore use in this case a shunt, which I make of a strip of damp felt, *r'*, having pins secured to its ends, and these pins I insert in the holes in pins *o o* when I wish to pass a very feeble current through the electrode.

Under some circumstances it is more convenient to have the electrode on a small handle, and I therefore use a wooden or other

handle, *T*, provided with a ferrule, *N*, and insulated metal socket *M*, to which the electrode may be attached. The connections are made in this case by cords with pin or plug terminals. The pin on one cord is inserted in a hole, *v*, in the ferrule *N*, and the pin on the other is inserted in a hole, *v'*, in the socket *M*, passing through a larger hole in the ferrule. This makes the terminals in the felt and in the metal nut, respectively. If, however, one of the pins be inserted in a hole, *v*, it will come in contact with both socket and ferrule and make the electrode one terminal. The construction of this device may be varied in many ways, and I have shown an instance in Fig. 4 which shows the construction of a device in which the drip-cup is omitted. The head *e* is extended to the requisite length and carries contact-springs that encounter the band *c*, connected with the carbon, and the pin *g*, which in this case is set in the insulating-stopper carrying the zinc.

Having now described in detail the construction of the apparatus, what I regard as new and of my invention, and desire to secure by Letters Patent, is—

1. The combination, with a portable case, of an induction-coil and battery, the battery having a zinc element carried by an insulating reversible plug or stopper adapted to close the battery-cell with the zinc either in or out of the same, as set forth.

2. The combination, with a portable case, of an induction-coil, a battery having a zinc element carried by a reversible plug or stopper, and a drip-cup fitting over the stopper and adapted to contain the zinc when the plug is reversed and the zinc removed from the battery, as set forth.

3. The combination, with an insulating handle or case, of an induction-coil, a battery with reversible plug carrying the zinc, a drip-cup fitting over the plug or stopper for containing the zinc when it is removed from the battery, and contacts composed of registering springs and plates, substantially as herein described, whereby the circuit from the battery to the coil is completed when the parts specified are brought together.

4. In an electrode, the combination of a metal cup, a central insulated metal nut, and a fibrous or felt strip held between the nut and the cup, and a band or ring for binding the edges of the felt over the sides of the cup, as described.

5. The combination, with an induction-coil and means for applying the induced currents to portions of the body, of a strip of dampened fibrous material connected to the induced circuit as a resistance-shunt to short-circuit more or less of the induced currents, as and for the purpose set forth.

6. The combination, with the case *A*, of the battery-cell *B*, the insulating plug or stopper *E*, carrying the zinc element and provided with a metal ring, *e*, in contact with the zinc, the

drip-cup F, adapted to fit over either end of the plug, and circuit-connections between the coil and battery, as set forth.

7. The combination, with the insulating case 5 or handle, a metallic ferrule or band, and an insulated metal socket carried by the case and forming electrical circuit-terminals, of a cup, as p, an insulated metal pin, p', contained therein, a felt pad or strip, t, metal nut s, and binding-ring t', all as set forth.

8. The combination, with a device for the local application of induced currents, consisting, essentially, of two circuit-terminals in close proximity, of a high-resistance shunt 15 formed by a damped strip of fibrous mate-

rial connected to the circuit, so as to short-circuit more or less of the current, as set forth.

9. In a double electrode for therapeutical purposes, the combination of a central metallic disk or plate, an outer encircling metallic rim 20 or plate, an interposed insulating-partition, an insulating-sleeve extending through the outer metallic rim or plate, and an electric conductor extending from the central disk or plate outwardly through said sleeve, as set forth.
